Focus-On Press Conference, Sep. 19, 2019, <https://www.youtube.com/watch?v=X47viKIQZ2M>.*Primary Examiner* — Keli L Hill(74) *Attorney, Agent, or Firm* — Emerson, Thomson & Bennett, LLC; Roger D. Emerson; Peter R. Detorre(57) **CLAIM**

The ornamental design for a valve, as shown and described.

DESCRIPTION

FIG. 1 is a rear elevation view of a valve.

FIG. 2 is a front elevation view thereof.

FIG. 3 is a left side elevation view thereof.

FIG. 4 is a right side elevation view thereof.

FIG. 5 is a top plan view thereof.

FIG. 6 is a bottom plan view thereof; and,

FIG. 7 is a top, front and left side perspective view thereof. The broken lines shown are included for the purpose of illustrating portions of the valve that form no part of the claim.
